(57) **CLAIM**

I claim the ornamental design for a jump pool cue, as shown and described.

DESCRIPTION

FIG. 1 is a front isometric view of a jump pool cue showing my new design;

FIG. 2 is a rear isometric view thereof;

FIG. 3 is a right side elevation view thereof

FIG. 4 is a front elevation view thereof; and,

FIG. 5 is a rear elevation view thereof.

A design top, bottom and left side elevation view have been omitted, as they are a mirror images of the right side elevation view of FIG. 3.
